UNITED STATES PATENT OFFICE

PAUL C. GALLAGHER, OF OMAHA, NEBRASKA

DESIGN FOR A FORK OR ANALOGOUS ARTICLE

Application filed April 17, 1931. Serial No. 39,535. Term of patent 3½ years.

To all whom it may concern:

Be it known that I, PAUL C. GALLAGHER, a citizen of the United States, residing at Omaha, in the county of Douglas and State of Nebraska, have invented a new, original, and ornamental Design for Fork or Analogous Article, of which the following is a specification, reference being had to the accompanying drawings, forming a part thereof.

Figure 1 is a plan view of a fork or analogous article, showing my new design.

Figure 2 is a transverse sectional view thereof, the view being taken substantially along the dotted line 2—2 of Figure 1, and

Figure 3 is a view of the opposite side of the fork to the showing thereof in Figure 1.

I claim:

The ornamental design for a fork or analogous article substantially as shown.

PAUL C. GALLAGHER.
